4,045,068 A 8/1977 Nelson 294/19
4,058,336 A 11/1977 Parkinson 294/19
4,063,769 A 12/1977 Zimmer 294/19
4,522,438 A 6/1985 Logue 294/19.2
4,811,980 A 3/1989 Ferrari et al. 294/19.2
5,069,451 A * 12/1991 Martens et al. 473/446
5,188,410 A * 2/1993 Summers 294/19.2
5,395,146 A 3/1995 Liu et al. 294/19.2
5,470,067 A * 11/1995 Diresca 473/446
5,505,510 A 4/1996 Duncan 294/19.2
D374,697 S * 10/1996 Meknight D21/721
5,639,133 A 6/1997 Mote 294/19.2
D411,278 S 6/1999 Sammons et al. D21/796
5,988,716 A * 11/1999 Liao 294/19.2

FIG. 2 is a right side view thereof;

FIG. 3 is a rear view thereof;

FIG. 4 is a left side view thereof;

FIG. 5 is a bottom view thereof;

FIG. 6 is a top view thereof;

FIG. 7 is a front view showing a second embodiment of my design for a combined puck retriever and carrier;

FIG. 8 is a right side view thereof;

FIG. 9 is a rear view thereof;

FIG. 10 is a left side view thereof;

FIG. 11 is a bottom view thereof; and,

FIG. 12 is a top view thereof.

The broken line showing of the hockey pucks and the internal features of the lower end of the device are for illustrative purposes only and form no part of the design.
